UNITED STATES PATENT OFFICE

2,080,236

MUFFLING DEVICE FOR COMPRESSORS

Christian Steenstrup, Schenectady, N. Y., assignor to General Electric Company, a corporation of New York

Application November 21, 1935, Serial No. 50,925

5 Claims. (Cl. 230—232)

My invention relates to muffling devices for compressors.

It is an object of my invention to provide a fluid muffling device for compressors, which requires a minimum number of parts, as well as a minimum alteration in the construction of the compressor in applying the muffling device thereto, which is simple and rugged in construction, and which is effective in operation.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a side elevation, partly in section, of a refrigerating machine including a refrigerant compressor provided with a muffling device embodying my invention; Fig. 2 is a fragmentary sectional view along the line 2—2 of a portion of the muffling device shown in Fig. 1, and Fig. 3 is a fragmentary sectional view of a portion of a modified form of muffling device which may be used on the refrigerant compressor shown in Fig. 1.

Referring to the drawing, I have shown in Fig. 1 a refrigerating machine, designed for household use, which includes a rotary type refrigerant compressor 10 provided with a substantially cylindrical outer compressor casing 11. The compressor 10 is driven by a vertical electric driving motor 12, the compressor being secured to the lower end of the driving motor. The compressor 10 and driving motor 12 are supported on a plurality of vertical helical compression springs 13 arranged at spaced intervals about the periphery of the motor 12. The upper ends of the springs 13 are secured by suitable bolts 15, to integral laterally projecting feet 14 formed on the motor frame. The lower ends of the springs 13 are tightly fitted on plugs 16 which are in turn rigidly secured to the bottom of a cylindrical hermetically sealed steel casing 17, which encloses the motor 12 and the compressor 10.

The compressor 10 is provided with inlet and exhaust ports 18 and 19, respectively. I have illustrated a device embodying my invention for muffling the sound of compressed vaporized refrigerant discharged from the exhaust port 19. This device includes outwardly extending annular integral reenforcing webs 20 and 21 formed on the compressor body or casing 11 and extending about the same. The webs 20 and 21

are arranged on opposite sides of the exhaust port 19 and in spaced relation thereto. A substantially cylindrical sleeve or closure member 22, made of cold-rolled sheet steel or the like, is supported on the webs 20 and 21 and extends about the compressor casing 11. The sleeve 22 thus cooperates with the webs 20 and 21 to form a fluid muffling chamber 23 adapted to receive compressed vaporized refrigerant discharged from the exhaust port 19. A series of vertical reenforcing webs 24 extend between the webs 20 and 21 and a notch 25 is provided in each of the vertical webs 24 in order that the muffling chamber 23 communicating with the exhaust port 19 may extend substantially entirely about the compressor casing 11.

The adjacent surfaces of the webs 20 and 21 and the sleeve 22 are arranged with relatively narrow portions thereof in alternate contacting and spaced relationship in order to form a plurality of restricted fluid outlet muffling passages 20 from the chamber 23 to the interior of the casing 11.

As illustrated in Figs. 1 and 2, a plurality of relatively narrow parallel notches or slots 26 and 27 are milled or otherwise formed in the edges of the webs 20 and 21, respectively, and extend transversely thereacross. The sleeve 22 thus cooperates with the notched portions of the webs 20 and 21 to define a plurality of restricted fluid outlet muffling passages 30 extending from the chamber 23 to the interior of the casing 11.

A body of lubricant 17a is maintained in the bottom of the casing 11, the lubricant being circulated to the moving parts of the compressor 10 by a pump 10a which is mounted on the bottom of the compressor. The lower edge of the sleeve 22 is preferably immersed in the body of lubricant 17a. Any lubricant which is entrained by the vaporized refrigerant in the compressor is discharged from the compressor into the chamber 23 and separates by gravity in the chamber 23 from the vaporized refrigerant. The lubricant thus separated from the refrigerant in the chamber 23 drains through the notches 26 formed in the lower web 20 and down the inner surface of the sleeve 22 back into the body of lubricant 17a.

In Fig. 3, I have illustrated a modified form of sleeve and web construction embodying my invention, and which may be applied to the compressor 10 shown in Fig. 1. A portion of a corrugated sleeve 22a is shown in Fig. 3, which may be substituted for the sleeve 22 shown in Fig. 1, and which cooperates with a smooth-edged web 28. The web 28 is similar to the webs 20 and 21, shown

in Figs. 1 and 2, except that its edge is smooth rather than being slotted. It will be seen that the adjacent surfaces of the sleeve 22a and the web 28, shown in Fig. 3, are arranged with relatively narrow portions thereof in alternate contacting and spaced relationship and the transverse corrugations 29 formed in the sleeve 22a co-operate with the web 28 to define a plurality of restricted fluid outlet muffling passages 30.

5 In the operation of the machine described above, vaporized refrigerant, such as methyl-formate, is compressed by the compressor 10 and discharged therefrom through the exhaust port 19 into the muffling chamber 23. Whether the 10 compressor 10 is of the rotary or reciprocatory type, the compressed vaporized refrigerant is ordinarily discharged therefrom in rapid puffs and, as a consequence, vibrations are set up in the compressed refrigerant of a frequency well above 15 the lower limit of the audible range. The compressed gaseous refrigerant in the chamber 23 passes therefrom through the fluid outlet passages formed by the notches 26 and 27 into the interior of the casing 17. Since the passages formed by 20 the notches 26 and 27 are very restricted in cross section, the vibratory motion of the compressed gaseous refrigerant passing therethrough is minimized. It will be noted that the cubic capacity of the chamber 23 is large as compared with the 25 placement of the compressor 10 and, consequently, the back pressure on the compressor 10 at the exhaust port 19 thereof is not unduly increased despite the restriction of the passages formed by the notches 26 and 27.

25 The compressed gaseous refrigerant thus discharged into the casing 17 passes therefrom through a conduit 31 into a refrigerant circulator passage 32 extending about a cylindrical natural draft air cooled condenser 33 which surrounds the 30 casing 17. The condenser 33 is of the sheet metal type and includes inner and outer sheets of metal 34 and 35 having complementary indentations 36 and 37 formed therein, respectively. The indentations 36 and 37 cooperate to form the refrigerant circulatory passage 32 between the adjacent surfaces of the sheets 34 and 35. The metal sheets 34 and 35 are rigidly secured together about their edges and between the indentations 36 and 37 formed therein throughout the length of 35 these indentations, preferably by closely spaced spot welds or line welding. The condenser 33 thus formed is supported on a series of radial heat conducting fins 38 which extend between the casing 17 and the condenser 33. The casing 17 is in turn supported on the upper side of a removable top wall 39 of the refrigerator cabinet with which the refrigerating machine is used. Cooling air circulates upwardly over the surfaces of the condenser 33 and between the condenser 33 and the 40 casing 17, due to natural draft, thus dissipating heat from the condenser 33, the casing 17, and the heat conducting fins 38. The compressed vaporized refrigerant in the refrigerant circulatory passages 32 of the condenser 33 is liquefied by the 45 transfer of heat therefrom through the cooling air passing over the surfaces of the condenser 33 and heat conducting fins 38. The refrigerant thus liquefied flows through a conduit 40 to a flow controlling float valve chamber 41 from 50 which it is supplied through a liquid line 42 to a sheet metal flooded type evaporator 43.

55 The evaporator 43 includes a pair of longitudinal cylindrical headers 44 and 45 extending along the upper edges thereof. The headers 44 and 45 are connected by a series of U-shaped refrigerant

circulatory passages 46 communicating therewith below the normal liquid level therein, and by a pressure equalizing conduit 47 communicating therewith above the normal liquid level therein. The headers 44 and 45 are maintained about 5 half full of liquid refrigerant and, as a consequence, the refrigerant circulatory passages are maintained flooded with liquid refrigerant. The evaporator 43 is supported on the lower side of the removable cabinet wall 39 within the food storage 10 compartment of the refrigerator which the evaporator is adapted to cool. The liquid refrigerant in the evaporator 43 is vaporized by the absorption of heat from the contents of the compartment in which it is located and the refrigerant thus vaporized is collected in the headers 44 and 45 above the level of the liquid refrigerant 15 therein. The vaporized refrigerant collected in the headers is returned therefrom to the compressor 10 through a conduit 48 which communicates with the header 44 above the liquid level therein. The opposite end of the conduit 48 communicates with the inlet port 18 of the compressor 10 through a hollow plug 49 having an inner end 50, which passes through a suitable hole 51 formed in the sleeve 22. The vaporized refrigerant thus returned to the compressor 10 is again compressed and the cycle, above described, is repeated and continued until the temperature of the compartment in which the evaporator 43 is 25 located is lowered to a desired value.

30 While I have shown a particular embodiment of my invention in connection with a household type refrigerating machine, I do not desire my invention to be limited to the particular construction shown and described and I intend, in the appended claims, to cover all modifications within the spirit and scope of my invention.

35 What I claim as new and desire to secure by Letters Patent in the United States is:

1. In combination with a refrigerant compressor comprising a substantially cylindrical casing having an exhaust port in the side wall thereof, outwardly extending webs on the exterior of said compressor casing and extending about the 40 same, said webs being positioned on opposite sides of said exhaust port, means including a substantially cylindrical sheet metal sleeve positioned on said webs and cooperating therewith for enclosing the outer end of said exhaust port to form a 45 fluid muffling chamber, the adjacent surfaces of at least one of said webs and said sleeve being arranged with relatively narrow portions thereof in alternate contacting and spaced relationship to form a plurality of restricted fluid outlet muffling 50 passages from said chamber.

55 2. In combination with a refrigerant compressor comprising a substantially cylindrical casing having an exhaust port in the side wall thereof, annular outwardly extending webs on the exterior 60 of said compressor casing and extending about the same, said webs being positioned on opposite sides of said exhaust port, at least one of said webs having a plurality of transverse slots formed in the edge thereof, and means including a substantially cylindrical sheet metal sleeve positioned on said webs and cooperating therewith for enclosing the outer end of said exhaust port to form a fluid muffling passage, the adjacent portion of said sleeve cooperating with said slots 65 in said one web to form a plurality of restricted fluid outlet muffling passages from said chamber.

70 3. In combination with a refrigerant compressor comprising a substantially cylindrical casing having an exhaust port in one wall thereof,

annular outwardly extending webs on the exterior of said compressor casing and extending about the same, said webs being positioned on opposite sides of said exhaust port, and means including a corrugated substantially cylindrical sheet metal sleeve positioned on said webs and cooperating therewith for enclosing the outer end of said exhaust port to form a fluid muffling chamber, the adjacent portions of at least one of said webs and said sleeve cooperating to define a plurality of restricted fluid outlet muffling passages therebetween communicating with said chamber.

4. In combination, a hermetically sealed casing, a compressor mounted in said casing, a lubricant reservoir in said casing below said compressor, means for supplying lubricant from said reservoir to said compressor, said compressor comprising a compressor body having inlet and exhaust ports therein, said compressor discharging compressed gas and entrained lubricant through said exhaust port, an outwardly extending web on said compressor body in spaced relation with respect to at least one of said ports, means including a cylindrical closure member surrounding said web for enclosing the end of said last mentioned port to form a fluid muffling and lubricant separating chamber, the adjacent surfaces of said web and said closure member being arranged with relatively narrow portions thereof in alternate contacting and spaced relationship to form a plurality of restricted fluid

muffling passages communicating with said chamber, certain of said passages being arranged to provide for returning lubricant to said reservoir from said chamber.

5. In combination, a hermetically sealed casing, a compressor mounted in said casing, a lubricant reservoir in said casing below said compressor, means for supplying lubricant from said reservoir to said compressor, said compressor comprising a substantially cylindrical vertical compressor body having an exhaust port in the side wall thereof, said compressor discharging compressed gas and entrained lubricant through said exhaust port, annular outwardly extending webs on said compressor body extending about the same, said webs being positioned on opposite sides of said exhaust port, means including a substantially cylindrical sheet metal sleeve positioned on said webs and cooperating therewith for enclosing the outer end of said exhaust port to form a fluid muffling chamber and lubricant separating chamber, the adjacent surfaces of said webs and said sleeve being arranged with relatively narrow portions thereof in alternate contacting and spaced relationship to form a plurality of restricted fluid outlet muffling passages from said chamber, the lower portion of said sleeve extending below the level of the lubricant in said reservoir to facilitate returning lubricant to said reservoir from said chamber.
